United States Patent Office

Des. 193,511
Patented Sept. 4, 1962

193,511

ELECTRICAL CONNECTOR CLAMP OR SIMILAR ARTICLE

Kenneth S. Hays, Philadelphia, Pa., assignor to
AMP Incorporated, Harrisburg, Pa.

Filed Aug. 7, 1959, Ser. No. 57,091

Term of patent 14 years

(Cl. D26—1)

The single FIGURE is a perspective view of an electrical connector clamp or similar article, showing my new design.

I claim:

The ornamental design for an electrical connector clamp or similar article, substantially as shown.
